UNITED STATES PATENT OFFICE.

CLARENCE G. WELSZ, OF PALMYRA, MISSOURI.

PORTABLE FENCE-POST.

1,008,227.

Specification of Letters Patent.

Patented Nov. 7, 1911.

Application filed December 14, 1910. Serial No. 597,256.

To all whom it may concern:

Be it known that I, CLARENCE G. WELSZ, a citizen of the United States, residing at Palmyra, in the county of Marion and State of Missouri, have invented certain new and useful Improvements in Portable Fence-Posts, of which the following is a specification, reference being had to the accompanying drawings.

10 My invention relates to portable fence posts and more particularly to that class which are provided with a separable base, which consists of molded blocks of artificial stone having a groove therein for the reception of a post that may be used for supporting fence wires, telephone wires, etc.

With the foregoing and other objects in view, the invention consists in the novel features of construction, hereinafter described, 20 pointed out in the claim, and shown in the accompanying drawings, in which—

Figure 1 is a perspective view of my improved fence post; Fig. 2 is a vertical transverse sectional view; and Fig. 3 is a perspective view of the auxiliary section thereof.

In constructing the improved fence post it will be seen in the drawings that the abutress is composed of two sections 1 and 2, which are suitably shaped blocks made of 30 artificial stone. The block 1 is provided with a sloping surface 3 on its inner side and in its outer side a longitudinal groove 4 is formed and extends to within a suitable distance from the base thereof. A fence 35 post 5 is secured therein by means of the bolt 6 passing through the block and post near the top end of the block. The post 5 is to extend a little beyond the outer surface of the block 1 as shown at 5' so that the fence wire may be secured thereto. The base of the post is held securely within the groove 3 by means of a dowel pin 7 having 40 one end set in the base block 1 at the lower end of the longitudinal groove 3, and an opening 8 in the base of the post 4 is adapted to receive the other end of said dowel pin. An inclined surface 9 is formed at the lower 45 end of the groove 3, for the purpose of affording means of escape for water which might get into the groove, and thus protect the post against decay from dampness, if the post be made of wood or other material which would become decayed from dampness. The blocks 1 and 2 are to be formed 50 with a concave bottom 10 so that if the

ground be uneven where the post is to be stationed it will allow the blocks to set firmly upon the ground and prevent any rocking movement thereof.

When the post is to be used in fencing in 60 cattle or other stock the wire is to be secured to the post 5' by staples or other suitable means, and when stock is to be placed on both sides of the fence the auxiliary block 2 is bolted on to the main block 1 by means 65 of the bolt 6 passing through the post and both blocks near the top ends thereof. A longitudinal groove 11 is formed on the inner side of the block 2 adapted to receive the extending edge 5' of the post 5, and the 70 lower edge of the fence wire or wires are to be placed between said blocks and when they are bolted together the wire will be held securely therein. This auxiliary block 2 is to be formed on its inner side with an inclined 75 surface 12 the same as the main block 1.

In setting up a fence the blocks 1 are to be placed on the ground a suitable distance apart and then the posts 5 are to be secured therein and the wire or wires are to be staked or otherwise secured to the posts. It 80 will be seen that a fence constructed with my improved post will be extremely simple in construction and inexpensive to manufacture, and will be the means of saving a good 85 deal of time and labor.

While I have shown and described the preferred form of my invention I do not want to limit myself to its exact construction, but desire to make such changes as 90 fairly fall within the scope thereof.

It will be noted that various changes in the details of construction and in the proportions may be resorted to for successfully carrying the invention into practice without 95 sacrificing any of the features or departing from the scope thereof.

Having thus described the invention what is claimed is:—

The herein described portable fence post 100 comprising the post member having upwardly converging sides, the base comprising a main section and an auxiliary section having mutually contacting inner side walls and respectively provided in their opposing 105 sides with recesses shaped to receive the lower end of the post member, the recess of the main section being deeper and broader than that of the auxiliary section and having a bottom inclined downwardly from the 110

auxiliary section, a securing pin fitted partly in that portion of the main section forming the bottom of said recess and partly in the post member, and a bolt extending trans-
versely through the sections of the base and also through the post member and binding them together.

In testimony whereof I hereunto affix my signature in the presence of two witnesses.

CLARENCE G. WELSZ.

Witnesses:

CLARENCE M. SHORES,
Mrs. CLARENCE SHORES.
